(57) **CLAIM**

The ornamental design for a hydroponic system, as shown and described.

DESCRIPTION

FIG. 1 is a perspective view of a first embodiment of a hydroponic system, taken from the front.

FIG. 2 is a front view of the first embodiment of the hydroponic system of FIG. 1.

FIG. 3 is a back view of the first embodiment of the hydroponic system of FIG. 1.

FIG. 4 is a left-side view of the first embodiment of the hydroponic system of FIG. 1.

FIG. 5 is a right-side view of the first embodiment of the hydroponic system of FIG. 1.

FIG. 6 is a top view of the first embodiment of the hydroponic system of FIG. 1.

FIG. 7 is a bottom view of the first embodiment of the hydroponic system of FIG. 1.

FIG. 8 is a perspective view of a second embodiment of a hydroponic system, taken from the front.

FIG. 9 is a front view of the second embodiment of the hydroponic system of FIG. 8.

FIG. 10 is a back view of the second embodiment of the hydroponic system of FIG. 8.

FIG. 11 is a left-side view of the second embodiment of the hydroponic system of FIG. 8.

FIG. 12 is a right-side view of the second embodiment of the hydroponic system of FIG. 8.

FIG. 13 is a top view of the second embodiment of the hydroponic system of FIG. 8.

FIG. 14 is a bottom view of the second embodiment of the hydroponic system of FIG. 8.

FIG. 15 is a perspective view of a third embodiment of a hydroponic system, taken from the front.

FIG. 16 is a front view of the third embodiment of the hydroponic system of FIG. 15.

FIG. 17 is a back view of the third embodiment of the hydroponic system of FIG. 15.

(Continued)

FIG. 18 is a left-side view of the third embodiment of the hydroponic system of FIG. 15.

FIG. 19 is a right-side view of the third embodiment of the hydroponic system of FIG. 15.

FIG. 20 is a top view of the third embodiment of the hydroponic system of FIG. 15; and,

FIG. 21 is a bottom view of the third embodiment of the hydroponic system of FIG. 15.

The dot-dashed broken lines depict portions of the hydroponics system and also represent a boundary of the claim that forms no part of the claimed design.
